DESIGN FOR A REFRESHMENT STAND

William B. Mann, Los Angeles, Calif., assignor
to Snack Spa Products, Inc., Los Angeles, Calif., a corporation of California

Application April 29, 1940, Serial No. 92,023

Term of patent 3½ years

To all whom it may concern:

Be it known that I, William B. Mann, a citizen of the United States, residing at Los Angeles, county of Los Angeles, State of California, have invented a new, original, and ornamental Design for a Refreshment Stand, of which the following is a specification, reference being had to the accompanying drawing, forming part thereof.

The figure is a perspective view of a refreshment stand showing my new design.

I claim:

The ornamental design for a refreshment stand,
substantially as shown.

WILLIAM B. MANN.
